UNITED STATES PATENT OFFICE.

LEO POTTER, OF NEW YORK, N. Y., AND ROBERT J. MOMPERE, OF NEWARK, NEW JERSEY; SAID MOMPERE ASSIGNOR TO SAID POTTER.

IRONING MACHINE.

Application filed August 25, 1921. Serial No. 495,336.

To all whom it may concern:

Be it known that we, LEO POTTER, a citizen of the United States, and a resident of New York, county and State of New York, and ROBERT J. MOMPERE, a citizen of the United States, and a resident of Newark, Essex County, State of New Jersey, have invented certain new and useful Improvements in Ironing Machines, of which the following is

10 a specification.

This invention relates to ironing machines.

In ironing machines of the type in which the material is ironed by feeding it under pressure over a heated element there is danger that the material may be scorched or burned if the heating element becomes too hot.

This invention has for its object to automatically release the pressure of the feeding element on the heating element when the latter reaches a predetermined temperature or before the material is scorched.

Another object of the invention is to provide an ironing machine with means for automatically cutting down the heat or reducing the temperature of the heating element when the element reaches a predetermined temperature or when the feeding of the material stops.

Another object of the invention is to provide an ironing machine with automatic control or regulating means whereby the temperature of the heating element will be maintained substantially constant and will be prevented from rising beyond a predetermined degree.

Further objects of the invention will appear from the following specification taken in connection with the drawings which form part of this specification.

In the embodiment of the invention illustrated the objects are attained by an ironing machine having a feeding element such as a roller, a heating element or shoe over which the material is fed under pressure by the roller, driving means for the roller, means for separating the roller and shoe when the feed is stopped and thermostatically controlled means for stopping the rotation of the roller or the feed of the material when

the heating element reaches a predetermined temperature. The thermostatic control means is also so constructed and arranged that the temperature of the heating element 55 or shoe will be automatically regulated.

Referring to the drawings:

Fig. 1 is a sectional elevation of an ironing machine constructed in accordance with our invention.

Fig. 2 is an end elevation partly in section of the construction shown in Fig. 1.

Fig. 3 is an enlarged detail view partly in section showing the mounting for the feed roller.

Fig. 4 is a rear elevation of a portion of the heating element or shoe.

Fig. 5 is a sectional elevation taken substantially on line 5—5 of Fig. 4.

Fig. 6 is a sectional elevation of the thermostat control mechanism.

Fig. 7 is an elevation and partly diagrammatic view showing the thermostat control for throttling the gas supply in the heating pipe, and

Fig. 8 is an elevation and partly diagrammatic view showing the thermostatic control mechanism in connection with electric heating mechanism for the ironing element.

The ironing machine shown in the drawings comprises a frame 20, a table 21 supported on the frame, a motor 22 supported in any suitable manner from the table and frame, a feed roller 23 and a heating element or shoe 24 having a heat indicator 24'. 80 85

The feed roller 23 has secured to its ends outwardly extending stub shafts 25 mounted in boxes 26 slidably mounted in slots 27 formed in brackets 28. As illustrated in Fig. 1 the brackets 28 are recessed as shown at 29 and are substantially L-shaped in outline and the portions 30 in which the boxes 26 are mounted are offset and are disposed entirely within the periphery of the roller thereby not interfering with the feeding of 95 material through the ironing machine, which is wider than the length of the roller and therefore has overlapping ends. Troughs 20' guide the material fed through the machine.

100 The feed roller 23 is driven from the motor 22 in the following manner. The motor

shaft 31 has a worm 32 thereon meshing with a worm gear 33 carried by a shaft 34. The shaft 34 telescopes with a shaft 35 which is splined thereto and the latter shaft 5 has a worm 36 meshing with a worm gear 37 secured to the roller shaft 38.

Means is provided for automatically moving the feed roller into feeding relation with respect to the ironing element or shoe 24 10 when the feed roller is driven. This is accomplished by means of a spur gear 39 rotatably mounted on the stub shaft 25, the gear having a laterally extending flanged or disc portion 40 formed thereon and engaging a disc 41 formed on the end of the feed roller. Suitable friction material 42 may be interposed between the discs if desired. A spring 43 presses the gear and disc 15 toward the feed roller thereby communicating the rotation of the feed roller to the gear 39. The gear 39 meshes with a rack 44 formed on an offset portion of the bracket 28. The driving connections just described are shown at both ends of the 20 roller and as the connections are exactly the same only one end has been described but corresponding reference characters have 25 been placed at both ends.

The driving operation of the feed roller 30 may be briefly described as follows. When the motor 22 is started the roller will be positively driven through the worm gearing described and this rotation of the roller will be communicated to the gear 39 by the friction clutch. As the gear 39 is rotated the roller will be moved in a direction toward the shoe 24 by reason of the fact that the gear meshes with the rack 44. As long as 35 the roller is driven, therefore, there will be a constant pressure maintained against the shoe 24. When, however, the roller is stopped this pressure will be relieved by means of a spring 45 in each of the brackets 28, the spring pressing against the box 26 in which the roller stub shaft is mounted. Upon the stopping of the feed, therefore, the 40 feed roller will be immediately and automatically separated from the shoe thereby relieving the pressure between these 45 elements.

The safety mechanism for automatically relieving the pressure between the feeding element and the heating element when the heating element reaches a predetermined 50 temperature, will now be described.

Referring particularly to Figs. 4-6 inclusive, the ironing shoe 24 is provided with a casing 46 on the back thereof and in the particular embodiment of the invention 60 shown in Figs. 1-7 the shoe is heated by means of gas conducted by a pipe 47. It should be distinctly understood that any form of heat such as steam, gasoline, or electricity as shown in Fig. 8, may be used 65 if desired. The shoe 24 has formed integral

therewith or secured thereto on its rear surface an outwardly extending box 48 and the thermostat controlling mechanism is mounted on a base 49 secured in the box 48.

Any suitable form of thermostat control 70 may be used and in the embodiment of the invention illustrated we have shown a thermostat comprising a pair of metallic strips 50 and 51 secured at one end, as shown at 75 52, to a block 53 carried by the base 49. The strips 50 and 51 are preferably made from steel and brass respectively since, as is well known, these elements expand unequally under the action of heat. At their free ends the strips have secured thereto a 80 contact member 54 adapted to coact with an adjustable contact 55 secured to the base 49. Contact 55 is carried by a screw 56 and a lock nut 56' secures the contact 55 in adjustable position. One terminal of an electric circuit is secured to the contact 55 and the other terminal of the circuit is secured to the stationary ends of the members 51 and 52. The electric circuit may have any suitable source of power such as a storage 85 battery, this circuit preferably being separate from the motor circuit.

The object of the thermostat mechanism just described is to control the motor circuit and to automatically regulate the heat 90 in the heating element or shoe 24. The thermostat may be designed if desired to be placed as shown in a relay circuit which in turn controls the motor circuit. One form of control circuit is shown in Fig. 7 100 where the thermostat is shown as connected in an auxiliary circuit having leads 60 and 61. One lead 60 is connected to one side of the thermostat at 62. The other lead 61 is connected to a solenoid coil at 63 and a wire 105 64 connects the other end 65 of the solenoid coil to the thermostat at 66.

The solenoid core 67 is loosely pivoted or connected by a pin and slot connection at 68 to an arm 69, which is secured to a pintle 110 70 of a throttle valve 71. The valve 71 is connected in the gas pipe 47 that supplies the gas burner 72 for the heating element or shoe 24. A hand controlled throttle 73 is also provided for the burner. 115

The solenoid core 67 also carries a pair of contacts 74, adapted to co-act with terminals 75 in the motor circuit.

The control mechanism just described operates as follows:

The thermostat circuit is normally open as shown in Fig. 6 and when the temperature of the shoe 24 exceeds a predetermined or safe limit the elements 50 and 51 expand, closing the contacts 54 and 55 and the circuit. This will energize the solenoid and actuate the core 67 thereby throttling or cutting down the gas supply and lowering the temperature of the shoe 24.

When the shoe is cooled or the tempera- 130

ture is lowered below the limit set the elements 50 and 51 will contract and open the circuit, de-energizing the solenoid and opening the gas throttle.

- 5 The solenoid core also controls the motor circuit and may be set to open this circuit if the shoe becomes too hot, thereby shutting down the motor and automatically separating the shoe and feed roller.
- 10 It should be understood that the motor control may be used with or without the throttle control and vice versa.

Referring to Fig. 8, we have shown an electrical heating element for the shoe. The 15 thermostat connections to the solenoid are the same as in Fig. 7 and corresponding parts are indicated by like reference characters in the two views. The solenoid core 67 is also loosely connected to an arm 69, 20 which in this case is secured to a quick-throw switch 80. The switch 80 controls the heater coil 81.

The heater circuit is connected to leads 25 82 and 83 and a hand control switch 84 is provided in this circuit.

The solenoid core 67 may also be connected as in Fig. 7 to control the motor circuit, if desired.

The operation of the thermostat control 30 shown in Fig. 8 is substantially the same as that shown in Fig. 7 except that the closing of the thermostat circuit operates the switch 80 to cut off the current from the heater coil 81.

35 When the motor is stopped, as above explained, the feed roller will stop rotating and will be immediately and automatically separated from the heating element or shoe 24 by the springs 45. It will thus be seen that when the heating element reaches a predetermined temperature the pressure between the feeding and heating elements will be immediately released thereby preventing the material being ironed from scorching or 45 burning.

In the operation of the ironing machine if the feed roller should be stopped for any reason as by a button or any large object between the shoe and roller the temperature 50 of the shoe would immediately rise as the rotation of the roller and feed of the material tends to dissipate some of the heat.

With the control mechanism last described, in operation, the rise in temperature 55 of the shoe would automatically cause the heating fuel to be shut off thereby preventing the scorching of the material. Under the conditions above outlined, also, the control mechanism, first described, would automatically stop the motor whereupon the 60 roller and shoe would be separated.

Although certain specific embodiments of the invention have been illustrated and described, it will be understood that the invention 65 is capable of further modification and

that changes in the construction and in the arrangement of the various co-operating parts may be made without departing from the spirit or scope of the invention as expressed in the following claims.

What we claim is:

1. In an ironing machine, a feeding element, driving means therefor, a heating element adapted to coact with the feeding element to iron the material and means for automatically stopping the feed of the material when the heating element reaches a predetermined temperature.

2. In an ironing machine, a feeding element, driving means therefor, a heating element adapted to coact with the feeding element to iron the material and means for automatically stopping the feed of the material and separating the feeding and heating elements when the heating element reaches a predetermined temperature.

3. In an ironing machine, a feeding element, a heating element, driving means for the feeding element, means for moving the feeding element toward the heating element, and means for automatically separating the feeding and heating elements when the heating element reaches a predetermined temperature.

4. In an ironing machine, a feeding element, a heating element, driving means for the feeding element, means for moving the feeding element toward the heating element, and means for automatically stopping the driving means and separating the feeding and heating elements when the heating element reaches a predetermined temperature.

5. In an ironing machine, a feeding roller, a heating element, driving means for the feeding roller, means for moving the feeding roller toward the heating element, and means for automatically separating the feeding and heating elements when the heating element reaches a predetermined temperature.

6. In an ironing machine, a heating element, a feeding element movable toward and from said heating element, a motor for driving said feeding element, means for moving the feeding element toward the heating element and means operable automatically when the heating element reaches a predetermined temperature for cutting off the power from the motor and for separating said elements.

7. In an ironing machine, a feed roller, a heating shoe, means for driving the roller, means for moving the roller toward the shoe and automatically operable means for separating the roller and shoe when the shoe reaches a predetermined temperature.

8. In an ironing machine, a feed roller, a heating shoe, means for driving the roller, means for moving the roller toward the shoe and automatically operable means for stopping the feed roller and separating the roller

and shoe when the shoe reaches a predetermined temperature.

9. In an ironing machine, a feed roller, a heating shoe, means for driving the roller, a means for moving the roller toward the shoe and thermostatically controlled means for separating the roller and shoe when the shoe reaches a predetermined temperature.

10. In an ironing machine, a feed roller, a motor for driving the roller, a heating shoe and automatically operable means controlled by the temperature of the shoe for stopping the motor.

11. In an ironing machine, a feed roller, a motor for driving the roller, a heating shoe, means for automatically separating the roller from the shoe when the roller stops rotating, and automatically operable means controlled by the temperature of the shoe for stopping the motor.

12. In an ironing machine, a heating shoe, a feed roller adapted to coact therewith to feed and iron the material, means for driving the feed roller, means for separating the roller and shoe when the feed stops, and automatically operable means controlled by the temperature of the shoe for stopping the motor.

temperature of the shoe for stopping the feed.

13. In an ironing machine, a heating element, a feeding element, means for maintaining a pressure of the feeding element against the heating element during the feeding movement and means controlled by the temperature of the heating element for automatically relieving said pressure. 30

14. In an ironing machine, a heating shoe, a feed roller, means for maintaining a pressure of the roller against the shoe during the rotation of the roller and means controlled by the temperature of the shoe for automatically relieving said pressure. 35

15. In an ironing machine, a heating shoe, a feed roller, means for maintaining a pressure of the roller against the shoe during the rotation of the roller and means controlled by the temperature of the shoe for automatically stopping the rotation of the roller and relieving said pressure. 40

In witness whereof, we have hereunto set our hands this 23rd day of August, 1921.

LEO POTTER.
ROBERT J. MOMPERE.
